SHIP PROPULSION DEVICE COMBINED WITH
HULL STRUCTURE

William Costa, San Diego, Calif.

Application July 24, 1950, Serial No. 175,567

4 Claims. (Cl. 114—77)

1

The invention relates to the propulsion of a ship by a unitarily attached, rather than built-in, power unit.

An object of the invention is to provide for the replaceable attachment to a ship's hull of one or more self-contained propulsion units.

Another object is to provide propulsion units of the character described which are adapted to be removed or replaced under either drydock or submergence conditions.

A further object is to provide for a particularly ready attachment and removal of propulsion units of the character described with respect to a ship's hull.

The invention possesses other objects and features of advantage, some of which, with the foregoing, will be set forth or be apparent in the following description of a typical embodiment thereof, and in the accompanying drawings, in which,

Figure 1 is a side elevation of a ship provided with a pair of propulsion units of my invention.

Figure 2 is an enlarged fragmentary side view of the stern portion of the ship, a lower hull portion being shown in axial section.

Figure 3 shows a present propulsion unit disposed in underlying spaced relation to the hull shown in Figure 2 and arranged for its vertical movement into attached relation to said hull, an upper portion of the unit being shown in longitudinal section.

Figure 4 is a plan view of the propulsion unit of Figure 3.

Figure 5 is a partly sectional view of the stern portion of the ship at the propulsion unit.

Figure 6 is a partly sectional view taken generally at the line 6—6 in Figure 5.

Figures 7 and 8 are fragmentary sectional views taken respectively at the lines 7—7 and 8—8 in Figure 5.

Figure 9 is a perspective view of the propulsion unit of Figures 3 and 4 having its hatch removed.

As illustrating a typical application of my invention, I have shown a ship 14 having a hull 15 provided with a pair of propulsion units 16 attached to its bottom in depending and unitary relation thereto. The present units 16 are similar and are particularly shown as disposed in mutually aligned relation beneath the keel line of the hull, with the rearward of said units disposed at the stern, or aft, portion of the hull. The skin of the hull at its sides and bottom 17 is suitably fabricated of plates which are backed by a frame structure including ribs in an appropriate hull structure.

A present propulsion unit 16 has a suitably

2

streamlined hull 21 of a general power-launch outline and structure, and has its gunwale 22 providing a continuous upper face 23 arranged for sealed engagement with and beneath an opposed complementary face portion of the ship's bottom 17 when the unit is attached to the ship's hull. As particularly shown, the upper gunwale face 23 is provided by a continuous frame 24 fixed to and along the inside of the sides of the unit hull 21, with said face flush with the top of the hull sides. Bolts 25 are suitably extendable from above through the ship's bottom and the gunwale frame 24 to engage in cap-nuts 26 fixed to and beneath the frame for clampedly fixing the unit against the ship's bottom, a suitable continuous gasket 27 being preferably interposed between the gunwale face 23 and the opposed portion of the ship's bottom 17 for water-sealing the connection.

The hull 21 of a unit 16 carries therein a suitable engine 29 which is arranged for its operation to drive a propeller shaft 30 which extends from the stern of the hull 21 and carries a suitable screw propeller 31 for use in propelling the unit and the ship to which it is attached, the driving power being transmitted from the engine shaft 29 to the propeller shaft 30 through a suitable variable speed transmission indicated at 32 and a clutch 33. The present engine 29 is assumed to be of the diesel type and to primarily receive its fuel through a pipe 34 extending from fuel tanks 35 provided within the ship's hull. An auxiliary fuel tank 36 is preferably provided within the unit 16 to provide fuel for the self-propulsion of the detached unit if such is desired. As particularly indicated, an electric starting motor 37 is provided for the engine 29, and the engine may be cooled by water drawn into and forced from the hull bottom 21' at a suitable valve assembly 38. Exhaust for the products of combustion of the engine may be provided at rear openings 39 of the unit hull. The displacement of a unit hull 21 preferably such, per se, that the detached unit may float on top of the water for its self-propulsion or towing thereon.

Each propulsion unit 16 is preferably provided with a rudder 31 at its rear end, said rudder being controllable by a stem 42 extending downwardly through the ship's hull and provided with a forked lower end 43 which is arranged to spannably receive the top edge of the rudder at or adjacent its axis of swinging, or be withdrawn upwardly into a receiving socket 44 in the hull bottom 17. Transversely extending steering arms 45 of the rudder may have tiller cables 46 extending forwardly therefrom to a suitable tiller con-

trol within the space of the unit hull 21 to provide for a rudder control when the unit 16 is detached from a ship and is to be propelled by its engine 29 or otherwise. In this manner, a rudder 41 is arranged for its independent control from within the ship and/or from within the unit 16, it being understood that the present unit rudders may provide the sole steering control for a ship to which the units are operatively attached.

A flange 24' extends inwardly from the bottom of the gunwale frame 24, and sealedly mounts on its upper face a plate member 51, which, with its securing bolts 51', lies below the plane of the gunwale face 23 and provides the top deck of the unit. Intermediately thereof, the deck member 51 is provided with a hatch opening 52 having a coaming 52' extending upwardly therefrom and arranged for the sealed mounting thereon of a hatch 53 to extend no higher than the gunwale face 23. Toward its ends, the member 51 is provided with collars 54 and 55 extending upwardly therefrom at openings 54' and 55' through the member, said collars being arranged for simultaneous and suitable sealed entry within the bottom ends of upright and appropriately spaced ventilator ducts 56 and 57 provided by the ship's hull 15 and respectively utilizable for providing fresh air within the unit 16 and for carrying away the combustion products of the engine 29. As indicated in Figure 7, the ventilator duct 57 may receive the engine exhaust from an exhaust pipe 29'' and is provided with a lateral branch 57' extending to a discharge point at a side of the ship's hull for optionally effecting an underwater exhaust discharge just below the water line and so against much less pressure than at the relatively deep exhaust openings 33 of the propulsion unit. When a unit 16 is detached from a ship, the collars 54, 55 may be suitably sealed, as by sealing discs 54'' and 55'' applied at their lower ends. Means are provided for sealing the lower ends of the ducts 56 and 57 when the collars 54 and 55 are removed therefrom; as shown, slide plates or gates 58 and 59 are provided in the ducts for positioning control from within the ship's hull.

Means are provided for an access connection of the hull spaces of a ship and an attached unit, said means generally comprising a closable opening 61 in the ship's bottom 17 opposite the hatch opening 52 of a propulsion unit fixed thereto. As particularly shown, a continuous coaming 62 extends upwardly in the ship's hull space about the opening 61 and is arranged to have a cover plate or hatch 63 sealedly and removably mounted thereon, as by means of bolts 64 connecting the coaming and cover, whereby the ship's bottom may be sealed at the opening 61 when no unit 16 is mounted opposite it. The opening 61 in the ship's bottom is preferably large enough to provide for the mounting or dismounting of the hatch 53 with respect to the deck opening 52 of a unit 16 when the unit is sealedly attached to the ship's hull in the described manner, and the cover 63 for the opening 61 is removable within the ship. When the mutually registering deck and bottom openings 52 and 61 are both open, the passage of operating personnel between the ship and unit is permitted, with the fuel pipe 34, and remote control and indicator lines for the engine, also conveniently extendable through the passage thus provided.

Having a present propulsion unit 16 sealedly fixed to the hull bottom 17, a release of the unit is arranged to be effected from within the ship's

hull by releasing the attaching bolts 25. If a unit 16 is to be removed while the ship is in drydock with the hull supported independently of the unit and the unit spaced from the drydock bottom, it is only necessary to lower the released unit on jacks or other supports to clear it from the hull. Should it be necessary, however, to release and salvage a unit 16 while it and the ship's bottom are submerged, it is first necessary to progressively seal the deck openings of the unit 16 and to seal the ship bottom opening 61 opposite the unit before the bolts 25 are released, and to thereafter admit water to the unit, as at the valve assembly 38 or at the engine exhaust openings 39 or at a special sea cock provided for the purpose, until the unit is gravitationally released from the hull bottom. A sealing of the deck openings of a unit 16 is arranged to be effected by applying the closure discs 54'' and 55'' to the collars 54 and 55 respectively from within the unit, disconnecting the portion of the pipe 34 which extends through the openings 52 and 61, mounting the hatch 53 on the coaming 51 from within the ship, and securing said hatch in place from outside and through the ship's bottom opening 61; if the unit 16 is not to be salvaged the sealing may be omitted. The sealing of the ship's bottom is arranged to be effected by operatively disposing the slide plates 58 and 59 in the ducts 56 and 57 respectively, and applying and securing the hatch 63 to the coaming 62 whereby the ship's bottom may be sealed against the entry of water therethrough before the unit is detached. It will be understood that the mounting of a unit 16 on the ship's bottom 17 is arranged to be effected by sealedly bolting the unit to the ship's bottom by the means provided, and then opening the vent and access passages which are provided to connect the hull and unit.

The present ship-propulsion device is understood to have a number of outstanding advantages in the art. For instance, an engine and propeller assembly of a present propulsion unit is a decided improvement over a usual built-in propeller installation in a ship's hull by reason of the shorter length of propeller shafts and shaft bearings needed, which directly results in a deeper propeller action, a minimized friction power loss between the engine and propeller, and an increased cargo capacity within the ship's hull. The present tandem use of the propulsion units 16 as attachments to a ship's hull bottom is understood to provide for a reduced hull strain, a better propeller action, a lowered center of gravity for the controlled ship, and an improved maneuverability of the ship by means of the spaced plural and independently controllable propellers and rudders provided.

Aside from the emergency detachability of the present propulsion units, it will be noted that the units may be interchangeable between ship's hulls arranged for their installation, and are adaptable for application in different numbers and positions with respect to ships' hulls generally. Also, a plural installation of the units on a ship's hull provides for an independent maneuvering control for each unit whereby a disabling of the power or steering equipment of one unit does not prevent further navigation of the ship. Should a ship provided with two propulsion units in tandem break apart between them to provide floating sections, as may happen under storm or war conditions, both pieces might be propelled and navigated independently.

From the foregoing description taken in con-

nection with the accompanying drawings, the advantages of the present ship propulsion device will be readily understood by those skilled in the art to which the invention appertains. While I have described the principle of operation, together with a form of my invention which I now consider to comprise a preferred embodiment thereof, I desire to have it understood that the showing is primarily illustrative, and that such changes and developments may be made, when desired, as fall within the scope of the following claims.

I claim:

1. In combination with a directly water-borne ship's hull, a separate self-contained propulsion unit having a relatively small displacement as compared with the displacement of the hull and provided with a drive means and a rudder, means detachably securing said unit to the hull bottom in sealed and fully submerged and fixed positional relation thereto, and means carried by the hull operative to control the operations of the attached unit and connected with the drive means and rudder.

2. In combination with a directly water-borne ship's hull, a pair of similar marine propulsion vessel units arranged for mutually independent surface operation and for fixing to the hull bottom and each provided with a rudder and a drive means, means detachably and sealedly fixing the units in tandem relation beneath the hull at the keel line thereof, and means carried by the hull for controlling the operations of the attached propulsion units.

3. In combination with a water-borne ship's hull, a separate self-contained propulsion unit

comprising a dirigible vessel of relatively small displacement, means detachably and directly operative at the gunwale of the vessel fixing it to and beneath the hull bottom in fully sealed and fixed positional relation thereto, and means carried by the hull operative to control the operations of the attached vessel.

4. In combination with a water-borne ship's hull having a bottom opening, a separate self-contained propulsion unit comprising a dirigible vessel of relatively small displacement providing a deck opening, means about said openings detachably fixing said unit to and against the ship's bottom in sealed relation thereto with the bottom hull opening and the vessel deck opening in mutual registration, sealing closures for each of said openings, and releasable means operative from within the hull space to mount or dismount said closures while the unit is attached to the hull.
